UNITED STATES PATENT OFFICE.

FREDERICK C. CROWE, OF CHICAGO, ILLINOIS.

CAR-COUPING.

SPECIFICATION forming part of Letters Patent No. 468,415, dated February 9, 1892.

Application filed March 9, 1891. Serial No. 384,252. (No model.)

To all whom it may concern:

Be it known that I, FREDERICK C. CROWE, a citizen of the United States, residing at Chicago, in the county of Cook and State of Illinois, have invented a certain new and useful Improvement in Systems for Coupling Cars and Distributing Fluid Through the Coupled Cars of a Train, of which the following is a full, clear, and exact specification.

10 My invention relates to improvements in car-couplings and fluid connections for cars, and has for its object to provide convenient means for controlling the car-coupling and fluid connections from a fixed point upon the 15 train—as, for example, a locomotive.

It is illustrated in the accompanying drawings, wherein—

Figure 1 is a view of the end of a car from beneath. Fig. 2 is a view of the center of the 20 car from beneath. Fig. 3 is a detail horizontal section of the coupling device. Fig. 4 is a cross-section on the line 4 4. Fig. 5 is a cross-section on the line 5 5. Fig. 6 is a detail plan view diagrammatic of the coupling-controlling mechanism. Fig. 7 is a detail 25 longitudinal section of the fluid connection of the valve. Fig. 8 is a detail of the rod connections. Fig. 9 is a cross-section of the same. Fig. 10 is a detail of the rod and pipe centering device. Fig. 11 is a detail of the double-check valve. Fig. 12 is a detail of the mechanism for controlling the three-way air-valve.

Like parts are indicated by like letters in all the figures.

30 A is the body of the car; B B, fluid-pipes passing thereunder and provided, respectively, with the bell-mouthing ends C C and the acorn-shaped ends D D, adapted to enter the bell-mouthing ends. Within the acorn-shaped 35 end is the valve D' on the stem D², which is guided by the block D³ and also by the block D⁴, and which projects so as to engage the end of the valve D⁵ in the bell-mouthing piece, which valve is on the stem D⁶ guided by the 40 block D⁷. The valve D⁴ is seated in the seat D⁸ and the valve D' in the seat D⁹. Suitable packing—as, for example, D¹⁰—may be used so as to insure a tight joint and the valve-seat may be made of any desirable material. 45 As to the operation of this detail of the device so far described, it is evident that when the cars come together the acorn-shaped end

will be received by and centered in the bell-mouthing piece and that the valve-stem D², projecting, will engage the valve D⁴, and thus 55 both of the valves D' and D⁴ will be forced from their seats. The springs D¹¹ and D¹², when the two parts are separated by the separation of the cars, will reseat their respective valves, and thus the pipes B B will be closed at 60 both ends on each adjacent car or connected from car to car on all adjacent coupled cars.

E E are rods beneath and parallel with the cars—one on each car—and provided, respectively, with the ends E' E' and E² E². These 65 ends are coupled to their respective rods by the universal joints E³ E³ and carry, respectively, the end E', the bell-mouthing piece E⁴, the end E², and wedge-shaped portion E⁵, which latter is adapted to enter the bell-mouthing piece. 70 The piece E⁴ is shaped within in the form of a wedge in cross-section, as shown in Fig. 9. The operation of this detail is sufficiently clear. When they are brought together so as to be coupled, each rod E, provided with the 75 end E² and the portion E⁵, will be coupled to its opposed rod by the entry of the part E⁵ into the part E⁴, and yet it will be loosely coupled, so that as one rod is rotated slightly 80 it will not engage or carry the other opposed rod, but will engage it so when and after first-mentioned rod has been rotated from a certain angle or distance.

It is desirable that the several rods and fluid-pipes should be properly centered, and 85 hence I employ the centering devices shown. They consist each of a case F, secured to the bottom of the car and provided with a central ring F' from which project rods F² F² in all directions, and which rods pass through the 90 case F. Interposed between the case F and the ring F', and about each of said rods, is the spiral spring F³, whereby the said ring is centrally disposed. Through this ring passes, as shown in Fig. 10, the pipe B, and of course 95 in like manner the rods E E or their respective ends E' E².

G G are bell-mouthing buffer-pieces centrally disposed and provided each with the draw head or bar G' G' on the rod G² G², 100 which rod passes through the box G³ and is surrounded by the spiral spring G⁴. This spring bears against the loose ends G⁵ G⁶ of the box, and against the end G⁶ bears the bell-

mouthed piece G, which of course will be suitably supported so as to be capable of longitudinal motion. The sides of the box are composed of the plates G⁷ G⁷, which are provided with shoulders to receive the sides of such box. From this it is evident that the buffer-bars G G are cushioned when they come together, and also that the pulling or drawing bars G G are also cushioned when they engage each other on the springs G⁴. Secured to the draw-head G² is the pendent arm G⁸, carrying the ball G⁹, whereby the rod G² is always normally held in proper position to bring the opposed hooks or ends of the draw-bars into proper relative relation. These draw-bars are provided with hook ends G', shaped as indicated in Figs. 3 and 4, which are adapted to engage each other when in a certain position and to be freed from each other when either is turned somewhat upon the axis of the rod G², so that by lifting the weight G⁹ and moving the rod G⁸ to one side, the bar G² will be rotated upon its axis and its hook end will be made to disengage the opposed hook end, and thus the cars will be uncoupled. The pipes B B are connected at the center of the car by the flexible connector J and are cushioned each upon the spiral spring J', which engages at one end the fixed 25 guide J² and at the other end the collar J³ on the rod B, and which also encircles the rod B. The rods E E do not require cushioning in the same degree, as there is sufficiently full play of the ends E⁵ within the pieces E⁴. The 30 two sections of the rods E E in each car are coupled together by the end E⁵ and a receiving-piece E⁴, as at the ends of the cars. K is an elbow crank-lever pivoted at K' beneath the car and provided with a long arm 35 which rests normally against the arm G⁸. To this long arm is secured the rod K², which is provided with a long slot K³ near the side of the car, through which passes the side handle K⁴, whereby from the side of the car the elbow crank-lever K may be rocked and the rod G² be turned upon its axis, so as to uncouple the cars. The cars may, however, be uncoupled by a fluid-pressure apparatus from the locomotive, as will now be described. The flexible portions J, which connect the respective 45 pipes B B, are each connected in the middle of the car and upon opposite sides of a pipe system L. In this pipe system, upon opposite sides of the connections from each pipe J, are situated valves L' L', which are normally closed toward such connection and open in the opposite direction and also open to the air. Each valve is controlled by a spring-actuated valve L², which keeps it in such described 50 condition. At each end of the system of pipes L is a coupling L³ L³, containing the double check-valve L⁴, provided with two valves seating in opposite directions and supported on the guide L⁵. From this coupling 55 and between the valve-seats passes the pipe L⁶, which opens into the expansible dia- phragm-chamber L⁷, the opposite side of which

is connected by the link L⁸ the arm L⁹ to the elbow crank-lever K. Fig. 6 shows these connections diagrammatically, as it were, to more clearly illustrate the fact that the fluid-pressure in the pipes B is communicated directly to the expansion-chamber L⁷ for the purpose of operating the elbow crank-lever K to rotate the draw-bars and thus uncouple the cars. The spring-handle of each of the valves L' is adjusted, as before stated, so as to keep the valves closed in the direction of the connection with the pipe B and keep it open in the opposite direction and also open toward the outside air. Now on the rod E, adjacent to the handle L², is the projecting finger M, adapted to engage the handle L² when the rod E is rotated, and if the rod E be rotated in a certain position and then retained in such position the adjustment is such that the valve will be closed to the outside air and will open connection from the pipe B and J into the pipe L and thence pipe L⁶. This finger M is pivoted upon the rod E at M' and has the projecting toe M², so that it will, when rotated in the direction indicated by the acorn, lift the handle L² of the valve, and thus bring it to the last-described position; but if the finger M is rotated farther it will disengage itself from the handle L². The operation of this detail is substantially as follows: If the engineer is provided with a connection of any convenient position with the rod E, which is at the front end of the train, whereby he can rotate the same, and also is provided with valves and the like, whereby to determine the supply of fluid to the pipes, he may first turn the rod E until the lost motion incident to the connection of the said several rods has been so far taken up as to bring a certain finger M on a certain desired car at a position where it will hold its associated valve in such a position as to open the connection from the pipe B through the pipe J, through the valve L' to the pipe L, through coupling L³, through the pipe L⁶ into the expansion-chamber L⁷. When this is done, he locks his rod in position or holds it in position and immediately turns a fluid-pressure into the pipe B. Inasmuch as the entire system of pipes connected with B is closed, except at the valve L', adjusted as just described, there will be a rush of fluid through such valve, and this will clear the opposed check-valve and send a current of fluid through the pipe L⁶ into the expansion-chamber L⁷, and thus move the link L⁸, lock the elbow-crank lever K, move the arm G⁸ to one side, rotate the draw-bar G², and release its hooked end from the opposed hooked end, whereupon the two cars will separate, being uncoupled. Immediately upon the separation of the cars, the valves in the pipes B will close, as provided for in the mechanism described in Fig. 7, the operation of which has been hereinbefore set out, but at the same moment, the rod E being released, will be rotated by the spring-actuated arm L², and the valve L' will be restored to 70 75 80 85 90 95 100 105 110 115 120 125 130

its normal position, in which position the fluid under pressure will escape from the expansion-chamber L⁷, pipe L⁶, &c., and the several parts, including the lever K, will be restored 5 to their original positions. The weight G⁹, descending to its normal position, will restore the draw-bar to its original and normal position for re-engagement with the next car with which it is brought in contact.

10 The use and operation of the devices have been sufficiently hereinbefore set out, and it is perhaps sufficient to add that in general the arrangement is such that with two cars approaching each other they automatically 15 couple themselves, and they also automatically place in connection two systems of pipes and two systems of rods, which are from that time on continuous throughout the train. Either of these rods may then be rotated, so 20 as to control the desired fluid-valve on the train, and the system of pipes properly associated with said rod may then be provided with a fluid-pressure, whereupon the desired car is disconnected or uncoupled from its 25 associated car. It may also be added that either of these systems of pipes may be used for distributing water, hot air, or steam, and the like for train purposes, as may be desired.

The bar-heads are beveled in the shape 30 shown in the drawings, so that when they engage each other one or the other, or both, will slightly turn, and the beveled portions of the heads will ride one upon the other, until the two heads have passed each other, when they 35 will approach into position and re-engage. A dial or indicator of some kind could be used in the locomotive-cab, for example, and could be connected with the devices for turning the rods, so that the indicator would show 40 which car had the open-valve connection, so that by this means the operator or engineer could determine which car should be uncoupled, and also know from the indicator when he had turned the rod far enough to uncouple that particular car.

The pipe connections when they come together meet upon elastic portions, as indicated in the drawings, for the portions about the acorn-shaped piece may be of rubber, 50 while the seat portion in the bell-mouthed piece will also be of rubber.

I claim—

1. The combination of a draw-bar capable 55 of rotation on its axis and provided with a laterally-projecting hook with a weighted

arm whereby the hook is kept normally in proper position to oppose the hook of the adjacent car, and a bell-mouthed buffer longitudinally movable along the car and from which such draw-bar projects, and a cushion 60 for such buffer.

2. The combination of a draw-bar capable of rotation on its axis and provided with a laterally-projecting hook with a weighted arm whereby the hook is kept normally in 65 proper position to oppose the hook of the adjacent car, and a bell-mouthed buffer longitudinally movable along the car and from which such draw-bar projects, and a spiral spring which serves both as a cushion for the 70 buffer when the same is pushed inwardly toward the car and also as a cushion for the draw-bar when the latter is pulled outwardly from the car.

3. The combination of a draw-bar supported so as to be capable of rotation on its 75 axis with a weighted projection therefrom to normally keep the same in proper position, a laterally-projecting hook, a hand-lever on side of car, a connecting-link, and a lever attached to said slide or link, resting against 80 arm on draw-bar, whereby said bar may be rotated to disengage it from adjacent car.

4. The combination of a loosely jointed or connected system of rods from one end of the 85 train to the other with a series of fluid-pressure pipes from one end of the train to the other, a device for uncoupling the cars, adapted to be operated by such fluid-pressure, and connections from the rod system to the pipe 90 system, whereby the former controls the application of the fluid in the latter to the device for uncoupling the cars.

5. The combination of a fluid-pipe system 95 with devices for uncoupling the cars, a valve controlling a passage-way from such pipe system to each of such devices, and a system of rods provided with a series of fingers adapted each to engage one of the valve-handles, said system extending from end to end of the train 100 and its members connected by a series of lost-motion devices, so that by turning the rod system on its axis any given valve may be thrown into proper engagement with its associated valve thus to uncouple any desired 105 car.

FREDERICK C. CROWE.
